UNITED STATES PATENT OFFICE.

DOUGLAS P. CARRITTE, OF NEW YORK, N. Y.

REFUSE-REDUCTION MACHINE.

No. 827,617.

Specification of Letters Patent.

Patented July 31, 1906.

Application filed January 26, 1906. Serial No. 298,085.

To all whom it may concern:

Be it known that I, DOUGLAS P. CARRITTE, a subject of the King of Great Britain, residing at New York, in the county of New York and State of New York, have invented certain new and useful Improvements in Refuse-Reduction Machines; and I do hereby declare the following to be a full, clear, and exact description of the invention, such as will enable others skilled in the art to which it appertains to make and use the same.

This invention relates to refuse-reduction machines, and has for an object to provide a machine adapted for digesting, draining, and drying refuse of any nature in a single receptacle and in practically a single operation.

A further object of the invention is to provide a refuse-reduction machine wherein the refuse is taken in its ordinary or natural condition and reduced to a dry and inodorous condition while continuously hermetically sealed, being dried at a temperature so low as to prevent ignition.

A further object of the invention is to provide a refuse-reduction machine capable of reducing to a dry condition refuse therein contained in the shortest possible time and with a minimum expense and labor.

Specifically the object of the invention is to provide a jacketed cylindrical receptacle mounted to rotate upon idlers and provided with means for the introduction of live steam during the rotation for digesting the contents, after which the surplus liquid is filtered off and the contained air exhausted. Live steam is then admitted between the cylinder and its jacket to heat the cylinder for drying the contents under vacuum, the vapor passing away through the vacuum-pipe.

With these and other objects in view the invention comprises certain novel construction, combinations, and arrangements of parts, as will be hereinafter fully described and claimed.

In the drawings, Figure 1 is a vertical longitudinal sectional view of the improved reduction-machine. Fig. 2 is a transverse sectional view of the machine, taken on line 2 2 of Fig. 1. Fig. 3 is a plan view of the perforate filter-bottom of the machine with the several constituent elements of said bottom so broken away as to show each. Fig. 4 is an enlarged detail view of a fragment of the receptacle and jacket as shown at the lower side of Fig. 2 and a transverse section of the parts shown in Fig. 3.

Like characters of reference designate corresponding parts throughout the several views.

In its preferred embodiment the improved reduction-machine forming the subject-matter of this application comprises a cylindrical receptacle 10, concentrically secured within the jacket 11, spaced therefrom at one end and completely around the said receptacle, except beneath the perforate bottom 12 formed in the receptacle. The bottom 12 is disposed within an opening in the periphery of the receptacle extending approximately throughout its length and occupying a small circumferential arc. The said perforate bottom is composed of a plate 13, having openings or thimbles 14, upon which is disposed a plate 15, having small perforations, with a filter fabric 16 secured upon the said plate 15 by means of the screen fabric 17. The several plates and fabrics are secured in position by means of clips 18, clamped upon the frame 19 by means of bolts 20 inserted through holes 21.

Within the receptacle 10 are secured the angle-irons 21, extending longitudinally of the receptacle and with one member of said angle-iron extending radially and inwardly from the shell of the receptacle. About the opening in the receptacle, upon which is secured the perforate bottom 12, is disposed a frame or liner 22, whereby the space between the perforate bottom and the jacket is separated from the space between the jacket and the receptacle, and communicating with the chamber thus formed is a pipe 23, provided with a cock 24 for withdrawing surplus liquid from the said chamber which passes through the perforate bottom into said member.

For charging the receptacle manholes are provided formed by the upstanding bosses 25 about one or more openings in the top of the said receptacle and closed by the cover 26, secured in any approved manner, as by the lever-nuts 27 upon the pivoted eyebolts 28. About the opening communicating with the said manhole a frame or liner 29 is disposed, whereby the space between the jacket and the receptacle is closed from communication with the said manhole.

About the casing is secured the bands 30, carried upon idlers 31, journaled in pillow-blocks 32, secured upon sills 33 or in any other approved manner. Opposite one of the bands 30 is secured a rack-ring 34, engaging the pinion 35, mounted upon the shaft 36, upon

which is secured one of the idlers 31, which is rotated by means of the friction-clutch (shown conventionally at 37) and driven in any approved manner from any approved 5 source of rotary motion.

At one end the receptacle is provided with a stuffing-box 38, through which extends a pipe 39 with an elbow 40 turned upwardly within the receptacle and terminating in an 10 upwardly-extending pipe 41 with a cap or cowl 42 upon its upper end. With the receptacle the pipe is provided with a T-coupling 43 and with a steam-pipe 44, connected therewith at right angles and with a valve 15 45, arranged to control the flow of steam through said pipe 44. The pipe 39 is continued by the pipe 46, into which the valve 47 is introduced and which communicates with any approved source of pneumatic 20 exhaustion. (Not shown.) At the end opposite the jacket is provided with a gland 48, through which extends a pipe 49 into the space at the end between the jacket and the receptacle. Without the jacket the pipe 39 25 is provided with an elbow 40, having a packing-box 50, arranged in axial alinement with the pipe 39 and through which extends a pipe 51, connected at its outer end with a steam-trap (shown conventionally at 52) 30 and with its inner end depending within and adjacent to the periphery of the jacket, as at 53. Connected with the elbow 40 is also a steam-pipe 54, into which is introduced the valve 55 for controlling the flow of steam 35 therethrough, and a manhole or hand-hole 56 with the usual and ordinary cover and cover-securings means is provided in the end of the jacket for obtaining access to the space between the jacket and receptacle.

40 For convenience the terms "bottom" and "top" have been employed in the description of this reduction-machine, it being understood that the said parts occupy such positions only when the cylinder is at rest 45 for charging or drawing off the surplus liquid and that at other times the cylinder rotates.

In operation the cylinder is held in the position shown in Figs. 1 and 2 by means of a 50 jack-like screw 56, bearing against either one or both of the bearing-bands 30, and by which means the cylinder is held rigidly in the said position and from accidental rotary displacement. To charge the device, the 55 manhole-covers 26 are removed and the refuse inserted therein in any approved manner and by the use of any approved means. When the approved quantity has been charged within the receptacle, the manhole-covers are secured firmly in position, and by 60 the manipulations of the valve 45 steam is admitted through the pipes 39 and 41 to the receptacle, the other valves, as 47 and 55, remaining closed. Power is then applied at 65 the clutch 37 to rotate the cylinder and by

reason of the steam therein admitted and the agitation produced by the rotation and the baffle-plates 21 the contents is quickly digested. When sufficient time has elapsed for the thorough digestion of the contents, 70 the cylinder is stopped in normal position and the cock 24 opened, which permits the surplus liquid to flow through the pipe 23, being forced therefrom by the steam admitted through pipe 44, being a press actuated by fluid-pressure. When the liquid has been drained out to the required extent, the valves 24 and 45 are closed and the valve 47 75 opened, whereby the air within the receptacle is exhausted through the pipe 46, producing thereby a partial vacuum within the receptacle. Steam is then admitted through pipes 54 and 49 to the chamber between the jacket and the cylinder, raising the temperature of the cylinder and its contents thereby, and the vapor produced by the drying process passes off through the pipes 41 and 46 into the vacuum-chamber. The water of condensation within the chamber between the jacket and the cylinder is drawn off 80 through the pipe 51 into the trap 52 in the usual well-known manner. By the use of this machine refuse of any and every nature may be introduced therein thoroughly digested, drained, and dried without leaving 85 the cylinder and without opening the manholes or any communication with the external air to permit the escape of foul odors or contained gases, all of the vapors and liquid passing off through the pipes as aforesaid 90 and into the usual sewer or other connection.

What I claim is—

1. In a device of the class described, a receptacle provided with a perforate bottom, and with a charging-opening at the top, a filter-cover for the perforate bottom, a closure for the top opening, means to introduce a digesting fluid into the receptacle, means to control the flow of contents from the perforate bottom, means to exhaust air from the receptacle, and means for introducing a heated fluid about the receptacle.

2. In a device of the class described, a receptacle provided with a perforate bottom, and with a charging-opening at the top, a filter-cover for the perforate bottom, means to control the flow of contents from the perforate bottom, a closure for the top opening, means to introduce a digesting fluid into the receptacle, means to exhaust air from the receptacle, and means for introducing a heated fluid about the receptacle.

3. In a device of the class described, a cylindrical receptacle provided with radial baffle-plates extending longitudinally thereof, and with a discharge-opening and a charging-opening, a perforate closure for the discharge-opening, a jacket secured about and spaced from the receptacle and provided with a charging-opening registering with the charg- 120 125 130

ing-opening of the receptacle, a removable closure for the charging-opening, a pipe piercing the wall of the jacket and arranged to discharge contents from between the jacket and cylinder and beneath the perforate closure, means to control the flow of material through the discharge-opening, circular bands embracing the jacket, idlers suitably journaled and arranged to carry the said bands and cylinders, means to rotate the said cylinders axially upon the said idlers, a pipe introduced through one end of and into the receptacle, means to admit steam through the said pipe, means to exhaust the air through the said pipe, a pipe introduced through the axis of the jacket at the opposite end, and communicating with a source of steam-supply, and with the space between the jacket and the receptacle, a pipe extending through the said pipe and curved downwardly within and to discharge liquid from the chamber between the jacket and receptacle, and communicating at its outer end with the steam-trap.

4. In a device of the class described, a cylindrical receptacle, a cylindrical jacket inclosing the receptacle, upon its peripheral sides and one end, a pipe piercing the axis of the jacket at the end inclosing the receptacle,

and arranged for connection with the source of steam-supply, a pipe piercing the axis of the receptacle at the end opposite and arranged for connection selectively with an exhaust mechanism, and a source of steam-supply, means to introduce and discharge material, and means to rotate the associated receptacle and jacket.

5. In a device of the class described, a cylindrical receptacle, surrounded by a cylindrical jacket spaced therefrom, the said receptacle being formed with an opening in its bottom communicating with the space between the said receptacle and jacket, a discharge-pipe piercing the wall of the jacket and communicating with the space between the jacket and receptacle, a cover for the opening in the bottom of the receptacle comprising a perforate plate overlaid by a fabric, and a division formed about the opening and filling the space between the receptacle and jacket.

In testimony whereof I affix my signature in presence of two witnesses.

DOUGLAS P. CARRITTE.
